UNITED STATES PATENT OFFICE.

SAMUEL B. H. VANCE, OF NEW YORK, N. Y.

REFLECTOR.

SPECIFICATION forming part of Letters Patent No. 229,212, dated June 22, 1880.

Application filed December 26, 1879.

To all whom it may concern:

Be it known that I, SAMUEL B. H. VANCE, of New York city, have invented certain new and useful Improvements in Reflectors, of 5 which the following is a specification.

My invention relates to that class of reflectors that are polygonal in shape and made with skeleton-frames, forming open sides, which are filled with segmental plates of glass; and the 10 invention consists in certain improvements in the details of construction, which will be hereinafter more fully described, and then pointed out in the claims.

Figure 1 of the drawings annexed presents 15 a side elevation of my improved reflector fitted for a pendent chandelier or number of lights. Fig. 2 is a sectional plan thereof on line x x , and Fig. 3 a vertical central section thereof.

20 The general form of the reflector is of the usual conical or similar convergent shape adapted for reflecting, and it is attachable to or connected with the gas-fixture in any of the usual modes. The frame of the reflector is of 25 skeleton form, as shown, and consists of a base-rim, a , which is formed with vertical lips on each margin, from which rim radial partition-ribs b converge to an upper rim, c .

The ribs of the frame are made of sheet 30 metal bent into form and soldered or riveted to the top and bottom rims. The ribs b b , as shown, are of T form, with outer overlapping flanges, n , while the upper rim, c , is formed with projecting ears d , which are bent inward 35 and downward, as shown. The ribs b thus divide the frame into a number of radial segmental panels or spaces, and these spaces are filled by plates e of opal glass, which are socketed or held in said panels around their margins, their lower edges resting on the base-rim 40 between the lips thereof, the side edges being overlapped by the T-flanges of the ribs, while the top edges are held by the ears d , bent in against the same. The reflecting-plates are 45 thus securely held in the panels, yet are exposed both on the outside and inside, which not only allows a portion of the light to pass through the plates and become diffused in the space above and around the reflector, but also 50 renders the construction lighter, simpler, and cheaper.

By the construction shown it will be observed that the reflecting-plates may be very readily fixed in or removed from the panels when desired, as their removal is allowed by 55 simply bending up the ears d d , while their fixation is obtained by the reverse action, as will be understood, thus conducing greatly to 60 simplicity and cheapness in the original construction, as well as allowing of any repairs, if subsequently required. This construction also admits of the ready removal or replacing of a 65 broken pane, when the reflector is fixed in the ceiling of a room, without the necessity of lowering the reflector out of its position, as by 70 simply bending up the lip a pane can be readily removed from the inside of the reflector, which cannot be done with the ordinary reflectors of this character.

By this described construction a reflector of 70 greatly-improved character is produced, for while being light, simple, and strong, and allowing a partial diffusion of the light, which for many purposes is quite desirable, its reflecting quality is much superior to what has 75 been previously employed, and the reflecting-surface is, moreover, quite indestructible. Thus the reflecting power of opal glass, or white porcelain, or similar pure white surface 80 is found to be much superior to metallic surfaces or mirror-plates heretofore used in this class of reflectors, while a serious objection to the latter is the oxidation or dimness caused by the action of the heat and air, which soon 85 impairs their reflecting power and renders my invention an important improvement over them.

Heretofore reflectors have been formed of a single piece of opal glass, and street-lamps have been constructed with a bottom rim provided with lips to hold the panes of glass in place at their lower ends and an upper rim provided with lips, which are bent from the inside down on the panes to hold them at their upper ends; but in this construction no ribs 90 are employed having outer longitudinal flanges to hold the panes. Moreover, a street-lamp is 95 not a reflector, and no opal glass is employed.

Reflectors have also been constructed with an upper and lower rim, connected by ribs having inner flanges, on which the panes rest, and the upper rim provided with lips turned down 100

upon the outer faces of the panes ; but in this construction the panes are removed and inserted from the outside of the reflector, and cannot be placed in position or removed therefrom from the inside, as in my invention, and hence when such reflector is inserted in a cavity in a ceiling, as is common, a broken glass cannot be removed or another inserted without taking down the entire reflector, as 5 the pane is removed or inserted from the outside of the reflector; whereas in my construction a pane can readily be removed in such case from the inside without taking down the reflector.

10 15 What I claim as my invention is—
The combination, with the circular base-rim

a, having vertical lips on each of its edges, and radial T-shaped ribs *b*, with outer flanges, *n* *n*, and projecting upper ends secured to the upper rim, of the upper circular rim, *c*, provided 20 with projecting ears *d*, turned inward and downward, and a series of panes of opal glass, *e*, fitting in the panels, and readily removed or inserted from the inside of the reflector, and so arranged as to reflect downward the greater 25 part of the light and transmit the remaining portion through them, substantially as described, and for the purpose set forth.

SAM. B. H. VANCE.
